UNITED STATES PATENT OFFICE.

ROBERT W. TURNER, OF WALNUT SPRINGS, TEXAS, ASSIGNOR OF ONE-HALF
TO EARNEST H. TURNER AND ROBERT T. TURNER, OF SAME PLACE.

BAKE-OVEN.

SPECIFICATION forming part of Letters Patent No. 651,786, dated June 12, 1900.

Application filed December 1, 1899. Serial No. 738,833. (No model.)

To all whom it may concern:

Be it known that I, ROBERT W. TURNER, a citizen of the United States, residing at Walnut Springs, in the county of Bosque, State of Texas, have invented certain new and useful Improvements in Bake-Ovens, of which the following is a specification, reference being had therein to the accompanying drawing.

This invention relates to bake-ovens, and particularly to an oven through which a current of cool or heated air may be passed to maintain the same at a desired temperature for either purposes of baking, evaporating, drying, or roasting substances therein, as may be found desirable.

The invention has for an object to provide a structure by which a current of either cool or heated air may be passed through the hot-air chamber and regulated in amount, so as to produce in said chamber any desired degree of temperature, thus adapting the chamber for a wide range of uses in which heat is applied to a greater or less extent to a substance to be dried or cooked.

25 A further object of the invention is to provide means by which the air may be introduced under pressure to the compartments of the hot-air chamber and passed through the same in either direction, as may be found desirable, for the purpose of changing the temperature of said chamber or maintaining a predetermined degree of heat therein.

Other objects and advantages of the invention will hereinafter appear in the following description, and the novel features thereof will be particularly pointed out in the appended claims.

The drawing forming part of this specification illustrates a longitudinal vertical section 40 through the apparatus, with a portion of the hot-air chamber in side elevation.

Like letters of reference indicate like parts in the drawing.

As illustrating a desirable form of the apparatus a cold-air chamber A has been shown, which may be of any desired configuration and is fed by means of a suction-fan A', having an inlet A² extending outward from the closed chamber A and a discharge A³ within 45 said chamber. This chamber may be of any desired construction or size, dependent upon

the amount of air to be supplied to the hot-air chamber B, with which the cold-air chamber communicates by means of one or more conducting-pipes C. This pipe is provided 55 with a coiled portion C' of any desired extent or configuration, located within a heating apparatus D. This apparatus may be of any preferred form or character; but for the purpose of illustration oil-burners D' have been 60 shown beneath the coiled portion and supplied from a reservoir D², above the same, while the chamber D is supplied with a suitable stack D³ to remove therefrom unconsumed products of combustion and provide 65 the necessary ventilation.

The hot-air chamber B is provided with a series of compartments B', with which the conducting-pipe C communicates by means of a branch C², provided with a regulating- 70 valve C³, thus introducing the heated air from the conducting-pipe at the lower portion of the compartment. At the upper portion of the compartment a discharge-pipe E is provided, which communicates with each of the 75 compartments B' by means of a branch E', provided with a valve E². The discharge-pipe E communicates with the cold-air chamber by means of a valved connection E³ and with the atmosphere by means of a similar 80 connection E⁴, whereby the heated air returned from the oven may be permitted to escape through the valve E⁴ when the valve E³ is closed, and when said valve E³ is opened the pressure in the cold-air chamber will be 85 reduced.

For the purpose of introducing cool or cold air in the compartments of the heated-air chamber for the purpose of moderating the temperature thereof or maintaining it at a 90 predetermined degree a conducting-pipe F is provided and communicates with the upper portion of each compartment by means of a valved connection F'. This pipe also is provided with a valve connection F² at its junction with the cold-air chamber. The air under pressure in this chamber can thus be introduced into the hot-air compartments by a proper regulation of the valved connections F'. At the lower portion of each compartment a cold-air-discharge pipe H is provided with a valve H', by which a downward cur- 95 100

rent of air may be produced through the compartment for the purpose of cooling the same.

The hot-air compartments may be provided with any suitable means for supporting there-in the material to be affected by the heated air. For instance, a roasting-drum G may be placed in one compartment and the other compartments provided with reticulated trays or baskets G', which support the material to be heated and permit the air to pass freely around the same. These trays are provided with suitable front plates G², by which a tight closure is effected, and with a transparent opening G³, by means of which the contents thereof may be inspected without removing the trays. The hot-air compartments may also be provided with a suitable thermometer G⁴ for indicating the degree of heat in each compartment, and it will be obvious that different degrees may be maintained in each of the compartments, so that different classes of work may be performed by the same apparatus at the same time. The roasting-cylinder may be rotated by any desired means, as may also the fan for producing an air-pressure within the cold-air chamber.

In the operation of the heating-chambers the valve C³ will be opened, as may also the valves E², thus admitting only heated air to the compartments and raising the temperature thereof to the desired degree. If it be desired, however, to remove from the compartments the air when laden with moisture or odors from the material cooked or dried, the valve E³ will be closed, and the heated air then escapes through the valve E⁴ to the outer atmosphere. Now if it be desired to reduce the temperature of the oven or maintain the same at a certain degree the hot-air valve C³ may be partly or completely closed and the cold-air valve F' opened. This introduces cold air into the compartments and reduces the temperature thereof. If it be desired to reduce this temperature quickly, the cold-air-discharge valve H' may be opened at the bottom of the compartment, thus creating a downward current of cold air through the compartment and effectually removing therefrom any heated air. It is also found desirable when introducing cold air to close the valve E³ of the upper discharge-pipe.

It will be obvious that the structure of the various parts of this apparatus may be formed of any desired non-combustible material and properly insulated to prevent the escape of heat, while the arrangement of valved conducting-pipes is such that any desired degree of heat may be maintained in each of the compartments independent of the remaining compartments, thus adapting the apparatus for different simultaneous operations—such as drying, roasting, and baking—while by a proper adjustment of the valves all of the compartments may be used for any preferred purpose.

It will be obvious that changes may be made in the details of construction and configura-

tion of the several parts of this apparatus without departing from the spirit of this invention as defined by the appended claims.

Having described my invention, what I desire to secure by Letters Patent is—

1. In a bake-oven, the combination with a cold-air chamber and means for producing a pressure of air therein, of a closed hot-air chamber, a conducting-pipe connecting said chambers, means for heating said pipe, a discharge-pipe leading from the upper portion of said hot-air chamber, and an independent cold-air pipe communicating with said cold and hot air chambers; substantially as specified.

2. In a bake-oven, the combination with a cold-air chamber and means for producing a pressure of air therein, of a closed hot-air chamber, a conducting-pipe connecting said chambers, means for heating said pipe, a hot-air-discharge pipe leading from said hot-air chamber, an independent cold-air pipe communicating with said cold and hot air chambers, and a cold-air-discharge pipe at the lower portion of said hot-air chamber; substantially as specified.

3. In a bake-oven, the combination with a cold-air chamber and means for producing a pressure of air therein, of a heated-air chamber provided with compartments, a conducting-pipe provided with a heating-coil and extending from said cold-air chamber to the lower portion of said compartments, means for heating said coil, and a cold-air-feed pipe communicating with the upper portion of said compartment and with the cold-air chamber; substantially as specified.

4. In a bake-oven, the combination with a cold-air chamber and means for producing a pressure of air therein, of a heated-air chamber provided with compartments, a conducting-pipe provided with a heating-coil and extending from said cold-air chamber to the lower portion of said compartments, means for heating said coil, a discharge-pipe communicating with the upper portion of said compartment, and a cold-air pipe communicating with said cold-air chamber and with the upper portion of said compartments; substantially as specified.

5. In a bake-oven, the combination with a cold-air chamber and means for producing a pressure of air therein, of a heated-air chamber provided with compartments, a conducting-pipe provided with a heating-coil and extending from said cold-air chamber to the lower portion of said compartments, means for heating said coil, a discharge-pipe communicating with the upper portion of said compartment, a cold-air pipe communicating with said cold-air chamber and with the upper portion of said compartments, a cold-air discharge at the lower portion, and suitable valves controlling the communication of all of said pipes with said compartments; substantially as specified.

6. In a bake-oven, the combination with a

cold-air chamber and means for producing a pressure of air therein, of a heated-air chamber provided with compartments, a conducting-pipe provided with a heating-coil and extending from said cold-air chamber to the lower portion of said compartments, means for heating said coil, a discharge-pipe communicating with the upper portion of said compartment, a cold-air pipe communicating with said cold-air chamber and with the upper portion of said compartments, a cold-air discharge at the lower portion, suitable valves controlling the communication of all of said pipes with said compartments, and reticulated supporting-trays within said compartments; substantially as specified.

7. In a bake-oven, the combination of a cold-air chamber, a pressure-fan located therein, a hot-air chamber provided with a series of compartments, a coiled conducting-

pipe extending from said cold-air chamber to the lower portion of each of said compartments, a heating-chamber, a burner therein beneath said coil, a discharge-pipe having valved connections with the upper portion of each compartment, a cold-air pipe having valve connections with the upper portion of each compartment and with the cold-air chamber, valved cold-air-discharge pipes at the lower portion of each compartment, and removable trays for supporting the material within said compartments, substantially as specified. 25

In testimony whereof I affix my signature in presence of two witnesses.

ROBERT W. TURNER.
